DESIGN FOR A BLOUSE

Delmar Meyer Mayehoff, Norwalk, Conn.

Application October 16, 1935, Serial No. 59,010

Term of patent 3½ years

To all whom it may concern:

Be it known that I, Delmar Meyer Mayehoff, a citizen of the United States of America, residing in Norwalk, county of Fairfield, and State of Connecticut, have invented a new, original, and ornamental Design for a Blouse, of which the following is a specification, reference being had to the accompanying drawing, forming part thereof.

I claim:

The ornamental design for a blouse, substantially as shown.

DELMAR MEYER MAYEHOFF.
